UNITED STATES PATENT OFFICE

ALFRED G. VON NORMANN, OF SEATTLE, WASHINGTON, ASSIGNOR TO TRUMBULL ELECTRIC MANUFACTURING COMPANY, PACIFIC DIVISION, OF SEATTLE, WASHINGTON, A CORPORATION OF WASHINGTON

SAFETY SWITCH

Application filed June 12, 1931. Serial No. 543,792.

This invention relates to safety switches of the type contained within a housing and operated by lever means on the exterior of said housing and the general object of this invention is to provide a switch of this nature having simple, compact and efficient means for effecting a quick and snappy break between contacts of the switch to thus reduce undesirable arcing when the switch is opened.

An important object of the invention is to provide a safety switch of this nature having quick break means which is positioned on the exterior of the switch box or housing and lies parallel to said housing and occupies a minimum amount of room and which makes possible the use of a switch box or housing of less depth than it would be possible to use if the quick break mechanism were located within the box.

Another object is to provide a safety switch of this nature in which the switch blades have a relatively long movement in proportion to the depth of the box and may be withdrawn into an open position a substantial distance away from the clips with which they normally make contact.

Patent No. 1,687,835, issued to Andrew E. Griswold on October 16, 1928, discloses a quick break safety switch in which the spring and other parts of the quick break mechanism are disposed within the switch box or housing. This necessitates a switch box of greater depth to provide room for said spring and quick break mechanism and to still afford room for ample movement of the switch blades. In accordance with my invention I place the quick break spring and parts of the operating mechanism on the exterior of the housing and arrange them parallel to the front wall of the housing so that they will not take up a great deal of room on the exterior of housing and will allow a more shallow housing to be used. Another advantage of placing the spring on the exterior of the housing is that it precludes danger of short circuiting of the switch by pieces of the spring in the event said spring should break. Other and more specific objects will be apparent from the fol-

lowing description taken in connection with the accompanying drawings.

In the drawings Figure 1 is a vertical mid-section of a switch constructed in accordance with my invention showing the switch closed.

Fig. 2, is a similar fragmentary sectional view showing the switch lever moved to the open position and the quick break spring compressed as it might appear just prior to snapping the switch open.

Fig. 3 is a view similar to Fig. 2, showing the switch open.

Figs. 4, 5 and 6 are detached perspective views of details of the quick break switch operating mechanism.

Fig. 7 is a cross section substantially on broken line 7—7 of Fig. 1.

Fig. 8 is a detached perspective view of the switch bar.

Fig. 9 is a fragmentary exploded perspective view of parts of the switch bar.

Like reference numerals designate like parts throughout the several views.

Referring to the drawings, 10 designates a rectangular housing having a removable front side 11 and having a panel 12 of insulating material disposed therein and secured to the bottom of said housing as by screws 13.

Mounted on said panel 13 by screws 14 are a plurality of sets of spring terminal clips 14 which are arranged for the reception of switch blades 15, 16 and 17 said clips being constructed so that they frictionally grip said blades when the switch is closed. Other terminal clips 18 and fuse plugs 19 may be provided in the usual manner on the panel 12. The switch blades 15, 16 and 17 are each secured between plates 20 and 21 of insulating material as by rivets 22. Other plates 23 of insulating material of shorter length are disposed between the plates 20—21 and form a support against which the outer or rear edges of the switch blades rest. The ends of all of said plates which project beyond the switch bars through a plate of insulating material 69 are slotted as at 24 to from T shaped heads 25 which are securely clamped within two channel shaped bars 26, said bars 26 being notched as at 27, Fig. 19 to receive the plates 20—21—23. The bars 26 are placed

with their open sides together and are secured in assembled position by screws 28 with the heads of the insulating blocks securely clamped within said bars.

5 Tubes 30 are also secured within the bars 26 and are slidably disposed on guide studs 31 which project upwardly from the bottom of the housing 10 and which serve to guide the bars for opening and closing movement of the 10 switch.

A switch operating link 32 is secured as by a clip member 33 to the bars 26 and extends outwardly through a slot 64 in the front wall 11 of the housing and through a slot 65 in a 15 bracket 66 which is secured as by screws 67 to the front wall of the housing. A thin plate 68 of insulating material fits loosely between the bracket 66 and housing wall 11 and covers the slot 64.

20 The outer end of the link 32 is positioned between the spaced apart upper ends of two plate members of similar construction which form a lever member hereinafter referred to as a secondary lever 34. A pivot 36 connects 25 said plate members with the end of said lever. This pivot is removably secured in place by a thin metal retaining member 36, Fig. 7, which is inserted between the plate members alongside of the end of link and is bent over 30 the head of the pivot 35. The plate members which form the secondary lever 34 are bent as at 37 so that the lower ends of said plate members lie flat against each other and these lower ends are inserted between the spaced 35 apart lower ends 38 of a two part switch operating lever 39. A pivot member 40 extends through ears 41 on the bracket 66 and through the ends of the switch operating lever 39 and secondary lever 34 thereby forming 40 a common fulcrum for said two levers.

The upper end of the secondary lever 34 is offset relative to the lower end thereof and is arranged to abut against and be stopped by the edge of said switch operating lever 45 when the two levers are in the relative position shown in Fig. 3. The two parts of the switch operating lever 39 are spaced apart at their lower ends and are brought together toward their upper ends and secured to each 50 other, preferably as by spot welding at 42, and are expanded or rounded above the said spot weld to form more convenient grasping means. An integral bell crank arm 43 on the pivoted end of the switch operating lever 55 39 extends inwardly toward the housing wall 11 and is provided on one edge with a spring engaging projection 44 which extends in the same direction as the lever. Another spring engaging projection 45 is provided on the 60 secondary lever 34 in opposed relation to the projection 44 and a compression spring 46 has its respective ends fitted over said projections and is interposed between the bell crank arm 43 and the secondary lever 34 so 65 as to yieldingly urge the secondary lever

against the switch operating lever as shown in Figs. 1 and 3 but to compress and allow said two levers to be separated, as shown in Fig. 2, when the switch operating lever is first moved to open the switch. Relative 70 separating movement of the two levers 34 and 39 is limited by engagement of the ends of the two projections 44 and 45, which engagement may occur when the two levers are in the relative positions shown in Fig. 2. Relative 75 movement of said two levers in the opposite direction is limited by engagement of the spread apart upper end portions of the secondary lever 34 with the adjacent edge of the lever 39.

In the operation of this safety switch when the levers 34 and 39 are in the position shown in Fig. 1, the switch will be closed, the blades 15, 16 and 17 will be frictionally held by the 80 clips 14 and the levers will be held in the upright position. To open the switch the operating lever 39 is pulled outwardly into a position as shown in Fig. 2, the result being that the spring 46 will first be compressed without moving the switch blades but will snap 85 the switch blades quickly into the open position shown in Fig. 3, as soon as the pull on the link 32 overcomes the frictional resistance exerted on the switch blades. If the 90 spring 46 is not strong enough to start initial 95 movement of the blades said movement will be started by positive engagement of the ends of the two projections 44 and 45 and when movement is thus started the blades will be 100 quickly snapped into their open position by the spring 46.

The foregoing description and accompanying drawings clearly disclose a preferred embodiment of my invention but it will be understood that this disclosure is merely illustrative and that such changes may be made as are fairly within the scope and spirit of the appended claims.

I claim:

1. In a safety switch a housing, a switch panel within said housing having spring terminal clips thereon, a switch bar guided for movement toward and away from said panel and having blades arranged to fit within and be frictionally held by said terminal clips, a link connected with said switch bar and extending outwardly through a wall of said housing, an operating lever pivoted externally of said housing for swinging movement toward and away from the housing, said operating lever being substantially parallel to the housing when the switch is closed, a short bell crank arm on the pivoted end of said operating lever extending inwardly toward said housing, a secondary lever having one end pivoted coaxial with said operating lever and the other end pivotally connected with the outer end of said link, said secondary lever and said bell crank arm respectively having oppositely disposed spring receiving 110 115 120 125 130

- projections thereon, and a compression spring on said projections between said bell crank arm and said secondary lever arranged to be compressed by opening movement of 5 said operating lever whereby said switch blades will be snapped into open position when the pull on said link overcomes the friction on said blades.
2. In a safety switch a housing, a switch panel within said housing having spring terminal clips thereon, a switch bar guided for movement toward and away from said panel and having blades arranged to fit within and be frictionally held by said terminal 10 clips, a link connected with said switch bar and extending outwardly through a wall of said housing, an operating lever pivoted upon the exterior of said housing for swinging movement toward and away from the housing, said operating lever being substantially parallel to the housing when the switch is closed, a short bell crank arm rigid with the pivoted end of said operating lever extending inwardly toward said housing, a secondary 15 lever having one end pivoted coaxial with said operating lever and the other end pivotally connected with the outer end of said link said secondary lever and said bell crank arm respectively having oppositely disposed 20 spring receiving projections thereon, and a compression spring on said projections arranged to be compressed by opening movement of said operating lever whereby said switch blades will be snapped into open position 25 when the pull on said link overcomes the friction on said blades, said two projections being arranged to abut against each other when the spring is fully compressed to insure the opening of the switch.
3. In a safety switch a housing, a switch panel within said housing having spring terminal clips thereon, a switch bar guided for movement toward and away from said panel and having blades arranged to fit within and be frictionally held by said terminal 30 clips, a link connected with said switch bar and extending outwardly through a wall of said housing, an operating lever pivoted upon the exterior of said housing for swinging movement toward and away from the housing, said operating lever being substantially parallel to the housing when the switch is closed, a short integral bell crank arm on the pivoted end of said operating lever extending inwardly toward said housing, and having a spring receiving 35 projection thereon, a secondary lever having one end mounted on the pivot of said operating lever and the other end pivotally connected with the outer end of said link, said secondary lever having a spring receiving 40 projection thereon, and a compression spring on said projection and disposed between said levers and said housing and arranged to be compressed by opening movement of said operating lever whereby said switch blades will be snapped into open position when the pull on said link overcomes the friction on 45 said blades.
5. In a safety switch, a switch bar embodying two channel members disposed with their open sides together, plates of insulating material held by said channel members and switch blades secured between said plates of insulating material.
6. In a safety switch, a switch bar embodying two channel members disposed with their open sides together, said channel members having notches in their adjacent edges, plates of insulating material having notches extending from the edges inwardly forming 50 T shaped heads which are held within said channel members and switch blades secured between said plates of insulating material.
7. In a safety switch, a switch bar embodying two channel shaped members disposed with their open sides toward each other and rigidly secured together, said bars having sets of notches in their adjacent edges which register with each other, plates of insulating material notched to form T shaped 55 heads which are held within and between said channel shaped members, the notched portions of said channel shaped members and said plates interfitting relative to each other, switch blades supported by said plates 60
8. In a safety switch a housing, a switch panel within said housing having spring terminal clips thereon, a switch bar guided for movement toward and away from said panel and having blades arranged to fit within and be frictionally held by said terminal 65 clips, a link connected with said switch bar and extending outwardly through a wall of said housing, a bracket on the exterior of said housing an operating lever pivoted on said bracket for swinging movement toward and away from the housing, said operating lever being substantially parallel to the housing when the switch is closed, a short integral bell crank arm on the pivoted end of said operating lever extending inwardly toward said housing, and having a spring receiving 70 projection thereon, a secondary lever having one end mounted on the pivot of said operating lever and the other end pivotally connected with the outer end of said link, said secondary lever having a spring receiving 75 projection thereon, and a compression spring on said projection and disposed between said levers and said housing and arranged to be compressed by opening movement of said operating lever whereby said switch blades will be snapped into open position when the pull on said link overcomes the friction on said blades.
9. In a safety switch, a switch bar embodying two channel members disposed with their open sides together, plates of insulating material held by said channel members and switch blades secured between said plates of insulating material.
10. In a safety switch, a switch bar embodying two channel members disposed with their open sides together, said channel members having notches in their adjacent edges, plates of insulating material having notches extending from the edges inwardly forming T shaped heads which are held within said channel members and switch blades secured between said plates of insulating material.
11. In a safety switch, a switch bar embodying two channel shaped members disposed with their open sides toward each other and rigidly secured together, said bars having sets of notches in their adjacent edges which register with each other, plates of insulating material notched to form T shaped heads which are held within and between said channel shaped members, the notched portions of said channel shaped members and said plates interfitting relative to each other, switch blades supported by said plates

and an operating link connected with said switch bar on the opposite side from said switch blades.

8. The apparatus as claimed in claim 7 in which tubular guide members are supported between said channel shaped members and three plates of insulating material are provided for each switch blade, the blade being held flatwise between two of the plates and 10 the edge of the blade resting on the other plate.

The foregoing specification signed at Seattle, King County, Washington, this 3rd day of June, 1931.
